G. B. JACKSON.

TORPEDO.

APPLICATION FILED JAN. 25, 1911. RENEWED DEC. 1, 1911.

1,373,246.

Patented Mar. 29, 1921.

UNITED STATES PATENT OFFICE.

GEORGE B. JACKSON, OF WESTMINSTER, MARYLAND.

TORPEDO.

1,373,246.

Specification of Letters Patent. Patented Mar. 29, 1921.

Application filed January 25, 1911, Serial No. 604,635. Renewed December 1, 1911. Serial No. 663,218.

To all whom it may concern:

Be it known that I, GEORGE B. JACKSON, a citizen of the United States, and a resident of Westminster, Carroll county, Maryland, 5 have invented certain Improvements in Torpedoes, of which the following is a specification.

My invention relates to track torpedoes employed for signal purposes, and it consists of certain improvements in the structure forming the subject-matter of my application for patent, filed January 27, 1910, Serial No. 540,354. The structure set forth in said application comprises a tubular envelop or container for the detonating material, which container performs the additional function of serving as the means for securing the torpedo to the rail head. Inasmuch as it is desirable to employ metal as 15 thin as possible, it may sometimes occur that the shell of the container is not sufficiently heavy to perform the desired function of serving as the retaining means. In order that it may be so employed I propose 20 to strengthen the ends of the metal container, and such construction is included in the subject-matter of my present invention. This and other features of my invention are more fully pointed out hereinafter, reference being had to the accompanying drawings, in which:

Figure 1, is a view illustrating a torpedo constructed in accordance with my invention, in the position of use upon the head of 35 a rail;

Fig. 2, is a perspective view illustrating a tubular body which may form the envelop or container of my improved torpedo;

Fig. 3, is a perspective view illustrating 40 the detonating charge inclosed in a suitable water-proof wrapper;

Fig. 4, is a similar perspective view showing a torpedo in a partly finished condition;

Fig. 5, is a perspective view illustrating 45 the finished crimped condition of the ends of the torpedo;

Fig. 6, is a sectional view of a torpedo on the line $a-a$, Fig. 5, showing also an outer layer or covering of paper;

Figs. 7, 8 and 9, are views in elevation of 50 the ends of modified forms of containers, said ends being partly crimped, and

Figs. 10, 11 and 12, are views illustrating 55 successive steps in the operation of crimping the ends of the tubular container shown in Fig. 2.

In the drawings, 1 represents a tubular container which may be made of metal alone, or of metal and fibrous material, such as paper, combined; the latter being preferably in the form of an outer cover or envelop for the tubular member. Into this tubular container a body of detonating material 2 is introduced, which may be and preferably is carried by a water-proof envelop 65 or wrapper 3; such body of material inclosed by the wrapper being shown in Fig. 3. The detonating material preferably occupies the middle third of the tubular container, and after it has been set in place, I 70 propose to crimp or squeeze the ends of the container tube beyond the body of detonating material in the manner clearly indicated in the drawings, so as to reinforce or stiffen said end portions which are designed to 75 serve as the means for securing the torpedo to the head of a rail, as indicated in Fig. 1. While this crimping or squeezing may be done in a number of ways, I may accomplish it in the manner indicated in the 80 drawings and more particularly referred to hereinafter, in which the sides of the tubes may be pressed in by suitable formers, and then the upper and lower portions between such sides may be pressed down, being sub- 85 sequently flattened when the formers are removed.

It will be understood, of course, that a torpedo embodying my invention may be constructed with a container substantially tubular, but not integral. In Figs. 7, 8 and 9, I have shown sectional views of the crimped ends of the torpedo container made of a plurality of pieces of metal. In using such form of container its value will be enhanced by an outer layer of paper which may be pasted down and covers the joints of the container. With such type of container, a body of detonating material such as shown in Fig. 3 may be employed, the 95 same as for the type of container shown in Fig. 2.

In the structure shown in Fig. 7, a container is shown made up of two pieces of sheet metal 1^a which may be joined at 1^b 105 and lapped at 1^c. In Fig. 8, the container is made of two pieces of metal 1^a each of which is connected by a seamed joint whereby a substantially tubular container is provided. The structure shown in Fig. 9 is 110 substantially the same as that shown in Fig. 8, except that the seamed joints are arranged

in a slightly different manner, with the side folds lapping; affording some additional reinforcing value.

In Figs. 10, 11 and 12, I have illustrated 5 means capable of effecting the crimping operation, although it will be understood that other mechanism may be employed for such purpose. In Fig. 10, the elements which may be employed for this purpose are shown 10 in position for the first stage or commencement of such operation.

The end of the container is indicated at 4, and it is shown with side grooves 5, formed by the members 6 which may be moved by 15 suitable means to the position shown. While in such position, an upper die, such as 7, may be brought down toward a lower die, such as 8, while still maintaining the side members 6 in place; the operation of said 20 dies 7 and 8 bringing the body of the container to the condition and shape shown in Fig. 11. The side groove forming members may then be withdrawn, and the upper and lower dies brought closer together so as to 25 finally flatten the folded ends of the torpedo container, as indicated in Fig. 12.

Instead of having the ends of the tube in the same plane as indicated in Figs. 10, 11 and 12, the side groove forming members 30 6 may be slightly offset vertically with respect to each other so as to cause said side folds to lap, the finished condition of the torpedo being substantially like that indicated in Fig. 9.

Fig. 5 shows a torpedo with the ends in 35 the finished crimped and reinforced condition. The folded ends are then ready to be clamped around the head of a rail, in the manner indicated in Fig. 1, when the structure is employed in use.

In the present form of my torpedo, the detonating material is preferably carried in 40 a water-proof jacket, and the container itself, whether integral or not, may be additionally strengthened by the use of a paper covering.

Although I have described and shown a 45 torpedo comprising a container for the detonating material made of metal in which the ends of the same form the means whereby the torpedo may be clamped to the head of a rail, it will be understood that a non-metallic shell, preferably waterproofed, may be combined with metallic parts, tubular or otherwise, so attached to the container 50 as to afford means for engaging or embracing the head of the rail and thereby hold the torpedo thereto. Such metallic parts may extend longitudinally of the torpedo container, or only at the ends thereof which engage the rail head.

The crimping or squeezing of the ends 65 of the torpedo container has the further effect of holding the detonating material in place; the crimping effect being carried

quite close to both ends of the inclosed material.

I claim:

1. A torpedo comprising a tubular container for an explosive, having its ends 70 crimped or corrugated, said ends forming clamping means whereby it may be secured to the head of a rail.

2. A torpedo comprising a tubular metallic container for an explosive, having its 75 ends crimped or corrugated, said ends forming clamping means whereby it may be secured to the head of a rail.

3. A torpedo comprising a tubular metallic container, having a body of detonating 80 material within said container, a covering for said container, and crimped ends forming means whereby said container may be clamped to the head of a rail.

4. In a torpedo, the combination of a substantially tubular element of metal forming 85 a container, a fibrous cover for the container extending from end to end of the same, and a body of detonating material located within said container, said container having 90 crimped ends forming clamping means whereby it may be secured to the head of a rail and the fibrous cover following the bends of said crimped ends.

5. A torpedo comprising a tubular metallic container, having a body of detonating 95 material within said container, and crimped ends serving to retain said body of detonating material in place forming means whereby said container may be clamped to the head of a rail, the crimping action reinforcing and strengthening said ends.

6. In a torpedo, the combination of a substantially tubular element of metal, a fibrous cover for the same, a body of detonating material within said container, and a frangible water-proof covering for said detonating material, said container having crimped 100 ends forming clamping means whereby it may be secured to the head of a rail.

7. A torpedo comprising a tubular container for an explosive, having its ends reinforced by corrugating the same, said ends forming clamping means whereby said torpedo may be secured to the head of a rail.

8. An improved railway torpedo comprising a tubular explosive inclosing case having integral extended and longitudinally folded rail-engaging members.

9. An improved railway torpedo, comprising a tubular explosive inclosing case having integral extended and longitudinally folded ductile rail-engaging members.

10. An improved railway torpedo, comprising an explosive inclosing case having 125 ductile extended and longitudinally folded rail-engaging members.

11. An improved railway torpedo, comprising an explosive inclosing case, having continuously formed ductile extensions, said 130

extensions being longitudinally folded and forming rail-engaging members with folded ends.

12. A torpedo comprising a tubular container for an explosive having longitudinally folded rail-engaging ends.

13. A torpedo comprising a tubular container for an explosive having crimped or corrugated rail-engaging ends.

14. A torpedo comprising a tubular metallic container for an explosive having longitudinally folded rail-engaging ends.

15. A torpedo comprising a tubular metallic container for an explosive having crimped or corrugated rail-engaging ends.

16. A railway torpedo comprising a tubular metallic container for an explosive charge having integral rail-engaging ends, said ends being reinforced by longitudinal folding of the portions of the metal container beyond the explosive-containing part.

17. A railway torpedo comprising a tubular explosive inclosing case, and a fibrous covering for said case, said case having integral extended and longitudinally folded rail engaging members with which the fibrous covering is interfolded.

18. A railway torpedo comprising a tubular metallic container having longitudinally folded rail engaging ends forming clamping means whereby it may be secured to the head of a rail, and a fibrous covering extending from end to end of said metallic container and interfolded with the rail engaging ends.

In testimony whereof, I have signed my name to this specification, in the presence of two subscribing witnesses.

GEORGE B. JACKSON.
